[57] CLAIM

The ornamental design for a novelty integrated circuit chip figure, as shown and described.

DESCRIPTION

FIG. 1 is a perspective view of a novelty integrated circuit chip figure showing my new design, the indicia on the top indicating a thermally responsive liquid crystal;

FIG. 2 is a top plan view thereof;

FIG. 3 is a bottom plan view thereof;

FIG. 4 is a left side elevational view thereof;

FIG. 5 is a front elevational view thereof;

FIG. 6 is a perspective view of a novelty integrated circuit chip figure showing a modified form of my new design, wherein the circuit chip is smaller and the liquid crystal is omitted.
